Term of patent 14 years

(Cl. D52—2)

Fig. 3

Fig. 2

Fig. 1

FIGURE 1 is a front elevational view of an automatic oil changer, showing my new design, the rear being essentially the same;

FIGURE 2 is an elevational view taken from one side thereof, the opposite side being essentially the same; and

FIGURE 3 is a front perspective view thereof taken from the side shown in FIG. 2.

The dominant features of the design reside in the portions shown in full lines.

I claim:

The ornamental design for an automatic oil changer, as shown and described.
